[57] **CLAIM**

The ornamental design for a handgrip for runner or similar article, substantially as shown and described.

DESCRIPTION

FIG. 1 is a perspective view of a handgrip for runner or similar article showing our new design;
FIG. 2 is a top plan view thereof;

FIG. 3 is a side elevational view thereof, the side opposite being substantially a mirror image;

FIG. 4 is a bottom plan view thereof;

FIG. 5 is a left end elevational view thereof;

FIG. 6 is a right end elevational view thereof;

FIG. 7 is a perspective view of a modified form of the design shown in FIGS. 1 through 6;

FIG. 8 is a top plan view of a third modified form of the design shown in FIGS. 1 through 6;

FIG. 9 is a side elevational view thereof, the side opposite being a mirror image;

FIG. 10 is a bottom plan view thereof;

FIG. 11 is a left end elevational view thereof;

FIG. 12 is a right end elevational view thereof;

FIG. 13 is a top plan view of a fourth modified form of the design shown in FIGS. 1 through 6;

FIG. 14 is a side elevational view thereof, the side opposite being a mirror image;

FIG. 15 is a bottom plan view thereof;

FIG. 16 is a left end elevational view thereof;

FIG. 17 is a right end elevational view thereof;

FIG. 18 is a top plan view of a fifth modified form of the design shown in FIGS. 1 through 6;

FIG. 19 is a side elevational view thereof, the side opposite being a mirror image;

FIG. 20 is a bottom plan view thereof;

FIG. 21 is a left end elevational view thereof;

FIG. 22 is a right end elevational view thereof;

FIG. 23 is a top plan view of a sixth modified form of the design shown in FIGS. 1 through 6;

FIG. 24 is a side elevational view thereof, the side opposite being substantially a mirror image;

FIG. 25 is a bottom plan view thereof;

FIG. 26 is a left end elevational view thereof; and,

FIG. 27 is a right end elevational view thereof.
